UNITED STATES PATENT OFFICE.

MICHAEL D. SCHALLER, OF DURHAMVILLE, NEW YORK.

ROOFING-TONGS.

1,151,053.

Specification of Letters Patent. Patented Aug. 24, 1915.

Application filed July 11, 1914. Serial No. 850,466.

To all whom it may concern:

Be it known that I, MICHAEL D. SCHALLER, a citizen of the United States, residing at Durhamville, in the county of Oneida 5 and State of New York, have invented new and useful Roofing-Tongs, of which the following is a specification.

The invention relates to improvements in roofing tongs.

10 The object of the present invention is to improve the construction of roofing tongs and to provide a simple, practical and efficient tool of strong, durable, and inexpensive construction, adapted to enable one man, 15 without the use of other tools, to do the work which usually requires two men, and equipped with means for clamping the upturned portions of the roofing sheets and for bending and squeezing the same to form 20 a smooth, water-tight seam.

With these and other objects in view the invention consists in the construction and novel combination of parts hereinafter fully described, illustrated in the accompanying 25 drawing, and pointed out in the claims appended hereto, it being understood that various changes in the form, proportion, size and minor details of construction, within the scope of the claims, may be resorted to 30 without departing from the spirit or sacrificing any of the advantages of the invention.

In the drawing, Figure 1 is an end elevation of roofing tongs constructed in accordance with this invention and shown open. Fig. 2 is a side elevation of the same. Fig. 3 is a similar view, partly in section, showing the opposite side of the tongs. Fig. 4 is an enlarged sectional view of the lower portion of the tongs, the clamping jaws being closed, and the crimping or bending jaw being open. Fig. 5 is a similar view, the crimping or bending jaw being closed. Fig. 6 is a detail sectional view showing 45 the jaws completely open. Fig. 7 is a detail sectional view on the line 7-7 of Fig. 1. Fig. 8 is a detail view of a portion of a seam having a double fold or lock.

Like numerals of reference designate corresponding parts in all the figures of the drawing.

In the accompanying drawing, in which is illustrated the preferred embodiment of the invention, the roofing tongs comprise, 55 in their construction, a main relatively fixed clamping or squeezing jaw 1 fixed to the

lower end of a main bar or lever 2 and cooperating with a relatively movable clamping or squeezing jaw 3, carried by the lower end of a lever 4. The main bar or member 60 2 is provided with a lower forked portion 5 having laterally extending terminals 6 fitted against and suitably secured to the outer face of the main relatively fixed clamping jaw 1. The clamping jaw 1, 65 which consists of a flat plate of suitable material, is equipped along its lower edge with an adjustable extension section 7 provided with upwardly extending arms 8 having slots 9 extending downwardly from the upper 70 ends of the arms and receiving screws 10 for clamping the lower extension section in its adjustment. The lower extension section 7, which is preferably of a thickness and length corresponding to the main relatively fixed jaw, is adapted to be adjusted 75 toward and from the same, and it constitutes a gage for regulating the height of the seam.

The relatively movable jaw 3, which is 80 preferably thinner and lighter than the main jaw 1, being tapered to a thin edge, is substantially coextensive in length with the fixed jaw and is provided at the lower edge with an outwardly extending flange 85 11 arranged at right angles to the engaging portion of the jaw, and secured to the lower end of the lever 4. The lever 4 is provided at its lower ends with attaching arms or portions 12, which are fitted against 90 the upper face of the said flange 11. The lever 4 is fulcrumed intermediate of its ends between transversely disposed arms 13 of the main bar or lever 2 by a bolt 14 or other suitable fastening device, and its upper end 95 is connected by a link 15 with one arm of an L-shaped operating lever 16. The arms 13 consist of flat plates or pieces spaced apart and rigidly connected with and extending from the main bar or lever at a 100 point intermediate of the ends thereof. The inner end 17 of the link 15 is bifurcated and the upper end 18 of the lever 4 is reduced to fit within the bifurcated end 17 of the link, to which it is pivoted by a rivet 105 19 or other suitable fastening device. The outer end of the link is pivoted by a rivet 20 or other suitable fastening device in a bifurcation 21 of the operating lever 16. The operating lever 16 is pivoted at its angle 110 in a loop 22 of the main bar or lever 2 by a pin 23 or other suitable fastening device.

The loop 22 extends longitudinally of the main bar or lever and constitutes the upper portion of the same. One arm of the L-shaped operating lever 16 extends outwardly from the pivot 23 to the link 15, and the other arm, which extends outwardly from the said pivot 23, is provided with a suitable grip or handle 24. The handle arm of the lever 16 is adapted to be swung upwardly and downwardly to oscillate the lever 4 for opening and closing the clamping or squeezing jaws of the roofing tongs. The opening movement of the clamping or squeezing jaws 1 and 3 is assisted by a spring 25 located in the space between the main bar or lever 2 and the lever 4, and fixed at its lower end in a slot 26 of a block or piece 27, which is rigidly secured between the arms of supporting portions 13 of the main bar or lever. The spring 25, which extends from the block or piece 27 to the upper portion of the lever 4, is loosely connected with the same by a link 28.

The main relatively fixed jaw 1 is provided at its ends with lugs or ears 29 projecting upwardly and inwardly from the upper edge of the said jaw 1 and having attaching portions 30 suitably secured to the outer face of the main clamping or squeezing jaw, but the lugs or ears may be formed in any other desired manner. The lugs or ears 29 have alined openings for the reception of terminal pivot portions 31 of a bending or crimping jaw 32 consisting of a flat plate or bar located above the jaws 1 and 3 and adapted to swing downwardly from the upwardly inclined elevated position shown in Fig. 6 to the closed position illustrated in Fig. 5. The bending or crimping jaw is provided with a central upwardly or outwardly projecting lug or ear 33, which is connected by spaced transverse links 34 with the lower end of an upright operating lever 35. The upright operating lever 35 is fulcrumed near its lower end between the outer portions of the arms 13 by a bolt 36 or other suitable fastening device, and its lower arm 37, which is relatively short, is arranged at a slight angle to the upper arm and is pivoted between the outer end of the links 34 by a rivet 38 or other suitable fastening device. The lever 4 extends through the space between the links 34 and the inner ends of the latter are arranged at opposite sides of the projecting lug or ear 33 and connected with the same by a pin or rivet 39. The upper terminal portion 40 of the upright operating lever is forked and is equipped with a grip or handle 41 extending across the space between and suitably secured to the sides of the fork.

The roofing tongs are adapted to form either a single or double seam, and in the formation of a seam, the upturned portions or flanges 42 and 43 of roofing sheets 44 are

gripped between the clamping or squeezing jaws 1 and 3 by manipulating the operating lever 16. The upper portion of the flange 43 is then folded downwardly by the bending or crimping jaw 32, which is actuated in such movement by the upright operating lever 35, said lever being swung inwardly toward the main bar or lever 2. In this movement of the bending or crimping jaw, the said upper portion of the flange 43 is bent downwardly against the exterior of the jaw 3, as illustrated in Fig. 5. The bend or fold is then completed by squeezing it between the clamping jaws 1 and 3. This forms a single lock seam, but a double lock seam 45 may be made by bending over or folding the upper portion of the seam by first manipulating the bending or crimping jaw and then completing the fold or bend with the squeezing or clamping jaws. In the formation of a double seam, these flanges, constituting the seam, will be made of sufficient height to enable two separate bending and crimping operations to be performed. In the performance of the second set of operations, a single seam, such as is shown in Fig. 5, is gripped between the clamping jaws a proper distance below the top of the seam, and the crimping jaw is then actuated to bend or partially fold the same. The operation is completed by placing the partially bent or folded seam between the clamping jaws and operating the latter to force the sides of the bend or fold into close contact with each other.

What is claimed is:—

1. Roofing tongs including a main bar or member provided at its lower end with a relatively fixed jaw, an upright lever pivotally connected at a point intermediate of its ends with the main bar or member and provided at its lower end with a relatively movable jaw, an operating lever mounted on the main bar or member and connected with the upper end of the upright lever, a spring rigidly connected at its lower end with the main bar or member and located in the space between the same and the upright lever, and a link pivotally mounted on the upright lever and loosely connected with the upper end of the spring.

2. Roofing tongs including a main bar or member provided at its lower end with a relatively fixed jaw, an upright lever fulcrumed at a point intermediate of its ends and connected with the said bar or member, a relatively movable jaw carried by the lower end of the upright lever, a pivotally mounted crimping or bending jaw, an upright operating lever fulcrumed at an intermediate point at the outer side of the first-mentioned lever, and a link connection between the lower end of the upright operating lever and the bending or crimping jaw.

3. Roofing tongs including a main bar or

- member provided at its lower end with a relatively fixed jaw, an upright lever fulcrumed at a point intermediate of its ends and connected with said bar or member, a 5 relatively movable jaw carried by the lower end of the upright lever, an operating member mounted on the bar or member and connected with the upper end of the upright lever, a pivotally mounted crimping or bending jaw, an upright operating lever fulcrumed at an intermediate point, and a link connection between the lower end of the upright operating lever and the bending or crimping jaw.
- 10 4. Roofing tongs including a main bar or member provided at a point intermediate of its ends with a laterally projecting support, an upright lever fulcrumed at a point intermediate of its ends on the support, a relatively fixed jaw carried by the lower end of the main bar or member, a relatively movable jaw connected with the lower end of the upright lever, a pivotally mounted crimping jaw, and an operating lever fulcrumed on 15 the said support and connected with the crimping jaw for operating the same independently of the relatively movable jaw.
5. Roofing tongs including a main bar or member having a relatively fixed jaw at its lower end and provided at an intermediate point with a laterally projecting support, an upright lever fulcrumed intermediate of its ends on the said support, a relatively movable jaw carried by the lower end of the upright lever, a crimping jaw pivotally mounted on the relatively fixed jaw, and an operating lever fulcrumed at an intermediate point on the support and connected with the crimping jaw and adapted to operate 20 the same independently of the relatively movable jaw.
6. Roofing tongs including a main bar or member having a relatively fixed jaw at its lower end and provided at a point intermediate of its ends with a laterally projecting support, a crimping jaw pivotally mounted on the relatively fixed jaw, an upright operating lever fulcrumed at an intermediate point on the said support, a link connecting 25 the lower end of the operating lever with the crimping jaw, and an upright lever fulcrumed at an intermediate point on the said support at a point between the main bar or member and the first-mentioned lever and provided at its lower end with a relatively movable jaw arranged to coöperate with the relatively fixed jaw.
7. Roofing tongs comprising a main bar or member provided at its lower end with a relatively fixed jaw, an upright lever, a relatively movable jaw fixed to the lower end of said lever, a bending jaw, an operating lever connected with the upright lever and pivotally mounted on the bar or member and projecting therefrom, an operating lever for 60 said bending jaw connected therewith, means for pivotally mounting the upright lever and bending-jaw operating lever in spaced relation at one side of the main bar or member and connected therewith, the two 65 operating levers having handles which are arranged for engagement by the hands of a single operator.
8. Roofing tongs comprising a main bar or member provided at its lower end with a relatively fixed jaw, an upright lever, means for pivotally connecting said lever to said bar or member, a relatively movable jaw fixed to the lower end of said lever, a crimping jaw, means for pivotally mounting the same on the fixed jaw, an operating lever connected with the upright lever and pivotally mounted on the bar or member and projecting therefrom near the upper end, an operating lever for said crimping jaw connected therewith, and means for pivotally connecting the last-mentioned operating lever to said bar or member, the two operating levers being provided with handles and arranged for engagement by the hands of a single operator.

In testimony, that I claim the foregoing as my own, I have hereto affixed my signature in the presence of two witnesses.

MICHAEL D. SCHALLER.
